(57) **CLAIM**

I claim the ornamental design for a gutter cover, as shown and described.

DESCRIPTION

FIG. 1 is a top perspective view of the gutter cover.

FIG. 2 is a top plan view thereof.

FIG. 3 is a front elevational view thereof.

FIG. 4 is an elevational view of the gutter cover taken from the right end of the gutter cover as shown in FIG. 2.

FIG. 5 is a perspective view of an alternate embodiment of the gutter cover; and,

FIG. 6 is a perspective view of the gutter cover of FIG. 5 shown in a position of use on a roof rain gutter. The dash lines showing the rain gutter and roof are for illustrative purposes only, and are not intended to form a portion of the claimed design.

The broken line showing of the rain gutter and roof in FIG. 6 are for the purpose of illustrating environmental structure and forms no part of the claimed design.
